MEASURING DEVICE

Sidney J. Finn, Beverly, Mass., assignor to United
Shoe Machinery Corporation, Paterson, N. J.,
a corporation of New Jersey

Application February 6, 1931, Serial No. 513,922

18 Claims. (Cl. 33—3)

This invention relates to measuring devices and is illustrated herein as embodied in a device for measuring the bottom surface of a cast of the lower portion of a foot.

5 It is well known that the bones of the foot are arranged substantially in the form of two distinct arches, a main or longitudinal arch extending from the os calcis to the heads of the first and fifth metatarsals and a secondary or transverse arch extending at the distal or front ends of the metatarsal bones transversely of the ball of the foot and forming a dome-like shape between the first and fifth metatarsals. This transverse arch forms a portion of and supports the forward end 10 of the longitudinal arch. The bones in these arches are not self-sustaining but are held in their respective arched formation by the fibrous, inelastic ligaments which unite them at their points of articulation, a strata of supporting muscles 15 being arranged next to the bones which by their contraction and relaxation produce motion and locomotion and enable the foot to support and to balance the weight of the body. From an examination of the bony structure of the foot it will be readily seen that the weight-bearing-points on 20 the human foot are the heel or os calcis and the heads of the first and fifth metatarsals. Normally these weight bearing points are in the same horizontal plane. However, as soon as the foot is placed in the usual heeled shoe the heel of the wearer is raised relatively to the forepart of the foot and consequently not only are the longitudinal and transverse arches of the foot displaced but the weight of the body is thrown more heavily 25 on the forepart of the foot because of the elevation of the heel. This displacement of the arches of the foot frequently causes the ligaments attached to the bones of the arches to become strained and stretched to such an extent that 30 there is a general subluxation of the various articulations which if not corrected will further result in a complete breaking down of the arches of the foot.

Since the bones of the foot are given their principal support by the ligaments and are only controlled by the muscles and their attachments it should be evident from the foregoing that if either the longitudinal or transverse arch of the foot is insufficiently supported by the ligaments 45 the muscular power of that arch will be insufficient properly to support and to balance its share of the weight of the body with the result that the weight-bearing points of the forepart portion of the foot will become displaced relatively to each 50 other and to the heel end of the foot, thereby

often imparting to the foot a tendency to roll toward one side or the other and eventually resulting in the muscles of the foot becoming completely unbalanced.

In my copending application for Letters Patent of the United States Serial No. 502,165 filed Dec. 13, 1930, there is disclosed a novel method of making lasts for use in the manufacture of corrective or orthopedic shoes. Shoes made upon these lasts are provided with extra space for the insertion of 10 filler pieces or foot molds between the feet of the wearer of the shoes and the inner surfaces of the soles of the shoes. These filler pieces are arranged to support the arches and muscles of the feet so as to correct weakness and deformity of 15 the arches and muscles and to restore proper anatomical posture to the feet. Accordingly, it is necessary that the positions of the arches of the feet of the individual for whom the shoes are to be made be accurately determined in order that 20 the shoes when completed will have the proper corrective influence on the feet.

In practicing the method disclosed and claimed in my copending application referred to above, casts are obtained of the feet of the wearer for 25 whom the shoes are to be made from impressions of the feet taken in a plastic material, the feet being positioned during the taking of the impressions so that the vertical center lines of the heel ends of the feet will be at right angles to the horizontal. 30

Since the bottom surfaces of these casts duplicate in detail the features of the bottoms of the feet from which they are made it will be readily seen that the positions of the arches of the foot 35 relatively to each other and to the heel end of the foot may be accurately determined by measuring the bottom surface of the cast with the vertical center line of the heel end thereof at right angles to a predetermined plane of reference. If these 40 measurements disclose a displacement of the arches of the foot, the inserted filler piece may be constructed with a transverse wedge, that is with one edge of greater thickness than the other so that the displaced arch will be lifted into corrective position. This lifting of the displaced arch relieves the strain on the muscles and ligaments 45 of that arch and tends to restore the entire muscular organization of the foot to a balanced condition.

In view of the above, it is an object of the present invention to provide a device constructed and arranged to facilitate the above-mentioned measuring operation. In the attainment of this object and in accordance with one feature of the in- 50

vention the illustrated device is provided with a frame and means for supporting a cast of the lower portion of the foot with the vertical center line of its heel end at right angles to a plane of reference formed on the frame. As illustrated herein the supporting means is adjustable relatively to the frame and, in accordance with another feature of the invention, means is provided for further controlling the position of the supporting means so that the heel end and one side of the forepart of the bottom surface of the cast may be positioned in or parallel to the plane of reference while the relation of the other side of the cast to the plane of reference is measured.

With the above and other objects and features in view the invention will now be described with reference to the accompanying drawing and pointed out in the claims.

In the drawing,

Fig. 1 is an isometric view of a device embodying the present invention;

Fig. 2 is a side view of the device shown in Fig. 1 with a cast of the lower portion of the foot in position to be measured; and

Fig. 3 is an end view of the device shown in Figs. 1 and 2.

The illustrated device comprises a frame consisting of a base 10 having side members 12, 12 secured thereto, the upper surfaces 14, 14 of which are in the same plane. A support or positioning plate 16 is provided having pins 18, 20 extending equal distances above its upper surface and a movable wedge 22. The wedge 22 is movable lengthwise of the support 16 in a guideway 24 by means of a handle 26. The support 16 is pivoted at 28 to the upper end of a swinging plate or lever 30, the lower end of which is pivoted at 32 to the base 10 of the device. A block 34 is interposed between the forward end of the support 16 and the upper surface of the lever 30, and is movable by means of a handle 38 lengthwise of the lever 30 in a guideway 36 formed on the upper surface of the lever 30. A second block 40, movable by means of a handle 42 lengthwise of the device in a guideway 44 formed on the upper surface of the base 10, supports the free end of the swinging lever 30. In operation the support 16 of the device is positioned normally in parallel relation to the base 10. A cast 50 of the lower portion of a foot is then placed in inverted position upon the pins 18, 20 and the wedge 22. The pin 18 is arranged to support the heel end of the cast in the center thereof while the opposite sides of the forepart of the cast are supported by the pin 20, and the wedge 22. It will be readily seen that the cast 50 may be rocked transversely or widthwise of the device on the pin 18 by movement of the wedge 22 either forwardly or rearwardly on the support 16 until the vertical center line 52 of the heel end of the cast 50 is located at right angles to the upper surface of the support 16 and to the plane of the measuring surfaces 14, 14. If the foot of the individual for whom the shoes are to be made is in a balanced muscular condition, that is, if the arches of the foot are not displaced, the opposite sides of the forepart of the cast 50 will be in the same plane as the base of the heel portion of the cast and in the plane of the measuring surfaces 14, 14 when the vertical center line of the heel portion is located at right angles to the plane of the upper surfaces of the side members 12. However, if the feet of the individual are in an unbalanced muscular condition the forepart of each cast 50 will be distorted relatively to the heel end thereof.

(Fig. 3), and consequently only one side of the forepart of the cast will be located in the same plane as the base of the heel portion of the cast and the surfaces 14, 14 are located. The blocks 34, 40 are movable in their respective guideways to position the bottom surface of the cast 50 with its heel end and at least one side of the forepart of the cast in the same plane with the surfaces 14, 14 of the side members 12, 12. With the cast 50 positioned as above described it will be readily seen that the positions of the arches of the foot relatively to each other and to the heel end of the foot may be accurately determined by measuring from the surfaces 14, 14 to the opposite sides of the forepart of the bottom surface of the cast 50. This may be done by taking measurements, for example, with a straight-edge 54 and a rule 56, from the plane of the surfaces 14, 14 to the opposite sides of the forepart of the bottom surface of the cast 50. If these measurements show the foot of the individual to be in an unbalanced muscular condition the inserted filler-piece may be constructed so that the foot will be supported in a proper corrective position.

Having described my invention what I claim as new and desired to secure by Letters Patent of the United States is:

1. A device of the class described comprising a frame having measuring surfaces located in a predetermined plane, means for supporting a cast of the lower portion of a foot with the vertical center line of the heel end of the cast at right angles to the plane of said measuring surfaces, and means for adjusting the supporting means to position the heel end and at least one side of the forepart of the bottom surface of the cast in or parallel to said plane.

2. A device of the class described comprising a frame having measuring surfaces disposed in a predetermined plane, means for supporting a cast of the lower portion of a foot with its heel end and at least one side of its forepart in or parallel to said plane, and means for adjusting said supporting means to position the vertical center line of the heel end of the cast at right angles to said plane.

3. A device of the class described comprising a frame having a pair of measuring surfaces disposed in a predetermined plane, means for supporting a cast of the lower portion of a foot with the vertical center line of the heel end thereof at right angles to said plane, and means for adjusting the last-named means to position the heel end and at least one side of the forepart of the bottom surface of the cast in or parallel to said plane.

4. A device of the class described comprising a frame having a pair of plane measuring surfaces formed thereon, means for supporting a cast of the lower portion of the foot, said means being arranged to rock the cast transversely to position the vertical center line of its heel end at right angles to the plane of the measuring surfaces, and means for adjusting the supporting means to position the heel end and at least one side of the forepart of the bottom surface of the cast in or parallel to said plane.

5. A device of the class described comprising a frame having measuring surfaces disposed in a predetermined plane, and means for supporting a cast of the lower portion of a foot comprising members for engaging the cast under the heel end and under opposite sides of the forepart, one of said members being adjustable to position the

vertical center line of the heel end of the cast at right angles to said plane.

6. A device of the class described comprising a frame having measuring surfaces disposed in a predetermined plane, and means for supporting a cast of the lower portion of a foot with the vertical center line of its heel end at right angles to said predetermined plane and for positioning the heel end and at least one side of the forepart 10 of the bottom surface of the cast in or parallel to said plane while maintaining the angular position of said vertical center line.

7. A device of the class described comprising a frame having measuring surfaces thereon disposed in a predetermined plane, and means for supporting a cast of the lower portion of a foot with the vertical center line of its heel end at right angles to said plane, said means being also arranged to position the heel end and at least one 20 side of the forepart of the bottom surface of the cast in or parallel to said predetermined plane while maintaining unchanged the angular relation of said vertical center line to said plane.

8. A device of the class described comprising a rectangular frame having measuring surfaces disposed in a predetermined plane, means for supporting a cast of the lower portion of a foot, said means being arranged also to rock the cast transversely of its longitudinal axis to position 25 the vertical center line of the heel end of the cast at right angles to the plane of the measuring surfaces, and means for rocking the cast longitudinally to position the heel end and at least one side of the bottom surface of the cast in or 30 parallel to said predetermined plane.

9. A device of the class described comprising a base, a support for a cast of the lower portion of a foot, means movable longitudinally of the support for rocking the cast transversely with 40 respect to the base, and means for rocking the support longitudinally with respect to the base whereby the heel end and at least one side of the forepart of the bottom surface of the cast may be positioned in the same plane.

45. 10. A device of the class described comprising a base having side members secured thereto the upper surfaces of which are in the same plane, a plurality of members for supporting a cast of the foot, means for relatively adjusting the supporting members to position the cast transversely of the device, and means for adjusting the supporting members relatively to the base whereby the heel end and forepart of the bottom surface of the cast may be moved into the plane of the 50 upper surface of the side members.

55. 11. A device of the class described comprising a base, a movable member carried by said base and having means thereon for supporting a cast of the lower portion of a foot with the vertical center line of its heel end at right angles to a plane of reference, said means being adjustable lengthwise relatively to said movable member, and means for adjusting the position of said movable member with respect to the base whereby the heel end and forepart of the bottom surface of the cast may be moved in or parallel to said plane.

60. 12. A device of the class described comprising a base having side members secured thereto the upper surfaces of which are in the same plane, an adjustable support carried by the base and having means thereon arranged to support a cast of the lower portion of a foot with the vertical center line of the heel end of the cast at right 65 angles to the upper surface of the support, and

means for adjusting the support relatively to the base whereby the heel end and the forepart of the bottom surface of the cast may be moved into the plane of the upper surfaces of the side members.

13. A device of the class described comprising a base having side members secured thereto the upper surfaces of which are in the same plane, an adjustable plate, means for supporting the plate above the base, means carried by the plate 10 constructed and arranged to support a cast of the lower portion of a foot with the vertical center line of the heel end of the cast at right angles to the upper surface of the plate, and means for adjusting the plate with respect to the base 15 whereby the heel end and forepart of the bottom surface of the cast may be moved into the plane of the upper surfaces of the side members.

14. A device of the class described comprising a base having side members secured thereto the upper surfaces of which are located in the same plane, an adjustable plate, means whereby said plate is carried by the base, a plurality of members carried by the plate and arranged to support a cast of the lower portion of a foot with the vertical center line of the heel end of the cast at right angles to the upper surface of the plate, and means for adjusting the plate with respect to the base 20 to the base to bring the heel end and at least one side of the forepart of the bottom surface 25 of the cast into the plane of the upper surfaces of the side members.

15. A device of the class described comprising a base having side members secured thereto the upper surfaces of which are in a common plane, 30 a swinging plate pivotally mounted on the base, a positioning plate pivotally secured to said swinging plate, means carried by the positioning plate for supporting a cast of the bottom portion of a foot, said means being constructed and arranged to support the cast with the vertical center line of the heel end of the cast at right angles to the upper surface of the positioning plate, and means for adjusting the positions of the plates 40 relatively to the base to bring the heel end and 45 the forepart of the bottom surface of the cast into the plane of the upper surfaces of the side members.

16. A device of the class described comprising a base having side members secured thereto the upper surfaces of which are in the same plane, 50 a swinging plate pivotally mounted on said base, a positioning plate pivotally secured to said swinging plate, means carried by the positioning plate for supporting a cast of the bottom portion of a foot, said means being adjustable relatively to the plate to position the vertical center line of the heel end of the cast at right angles to the upper surface of said positioning plate, a wedge member interposed between the base and 60 the swinging plate, a second wedge member interposed between the swinging plate and the positioning plate, and means for moving the wedge members toward and away from each other to position the heel end and at least one side of 65 the forepart of the bottom surface of the cast in the plane of the upper surfaces of the side members.

17. A device of the class described comprising a base having side members secured thereto the upper surfaces of which are in the same plane, 70 an adjustable plate, means whereby said plate is carried by the base, a plurality of supports carried by the plate and arranged to engage the heel end and the opposite sides of the forepart 75

- of a cast of the lower portion of a foot, one of
said supports being adjustable relatively to the
plate to position the cast with the vertical cen-
ter line of its heel end at right angles to the
5 upper surface of the plate, and means for adjust-
ing the plate with respect to the base whereby
the heel end and the forepart of the bottom sur-
face of the cast may be moved into the plane
of the upper surfaces of the side members.
- 10 18. A device of the class described comprising
a base having side members secured thereto the
upper surfaces of which are in the same plane,
an adjustable plate, means whereby said plate is
carried by the base, said plate having pins ex-
15 tending equal distances above its upper surface
- and arranged to support the heel end and one
side of the forepart of a cast of the lower por-
tion of a foot, a wedge also carried by said plate
and arranged to support the opposite side of the
forepart of the cast, said wedge being adjustable
lengthwise of the plate to position the cast with
the vertical center line of its heel end at right
angles to the upper surface of the plate, and
means for adjusting the plate longitudinally
whereby the heel end and the forepart of the 10
bottom surface of the cast may be moved into
the plane of the upper surfaces of the side mem-
bers. 5
